UNITED STATES PATENT OFFICE.

JAMES L. BREESE, JR., OF CHICAGO, ILLINOIS.

OIL PILOT LIGHT.

Application filed August 1, 1925. Serial No. 47,450.

My invention relates to a burner for liquid or gaseous fuels and a method of their combustion and particularly to an oil pilot light for use with an oil burning heating apparatus. One object of my invention is to provide a pilot light which shall burn the same fuel as the oil burning installation with which it is used. Another object is the provision of a pilot light of the type described, the flame of which shall deposit little or no carbon on the surfaces exposed thereto. Another object is the provision of a pilot light of the type described wherein the combustion shall be steady and uniform. Another object shall be the provision of a pilot light in which the flame shall be under pressure. Other objects will appear from time to time in the course of the specification and claims.

I illustrate my invention more or less diagrammatically in the accompanying drawings wherein:

Figure 1 is a side elevation of the installation;

Figure 2 is a detail side elevation on an enlarged scale;

Figure 3 is a vertical section through the parts shown in Figure 2;

Figure 4 is a plan view of the fuel connections; and

Figure 5 is a horizontal section on an enlarged scale on the line 5—5 of Figure 1.

Like parts are designated by like characters throughout the specification and claims.

A is any suitable furnace, the details of which form no part of the present invention, having the floor A¹, the forward wall A², and an opening A³ therein.

B is any suitable fire pot or combustion chamber, positioned in the furnace, for the combustion of the hydrocarbon or other liquid or gaseous fuel desired to be burned.

B¹ is a fan driven by any suitable motive means, not herein shown, and connected by means of the air passage B², through the furnace aperture A³, with the combustion chamber B.

C is any suitable fuel supply tank from the lower portion of which extends the fuel line C¹ which may be controlled by the hand valve C². It extends to any suitable float chamber C³, the details of which form no part of the present invention. Extending from the float chamber C³ is the fuel line C⁴. C⁵ is any suitable metering valve, and C⁶ is a fuel line of restricted cross section,

extending thence to the casing C⁷ associated with the air passage B².

D is a T in the fuel line C⁴, to receive the pilot fuel line D¹. D² is any suitable metering valve therefor. D³ is a fuel line extending to the pilot burner assembly D⁴ and connected with the line D¹ by the T D⁵. One arm of the T is closed by the apertured plug D⁶ through which passes the cleaning rod D⁷, extending throughout the length of the line D³, and terminating, as at D⁸, at a point within the pilot burner assembly. D⁹ is any suitable packing for the rod, held in position, for example, by the apertured cap D¹⁰.

The pilot light assembly generally indicated as D⁴, includes an interior combustion chamber aperture, F, surrounded by the annular wall F¹ which is provided with a plurality of perforations F². F³ is an exterior annular chamber closed by the circumferential casing wall F⁴, and connected by the air line F⁵ with the secondary fan or blower F⁶ which may be actuated, for example, by a secondary motor means not here- 80 in shown.

The top wall F¹⁰ of the pilot light chamber is shown with an upturned annular flange F¹² inset in the bottom of the firepot B. F¹⁴ is an aperture in the firepot bottom, herein shown as of smaller cross section than the corresponding aperture F¹² of the wall F¹⁰.

I provide in the closed bottom F of the pilot light chamber a layer G¹ of sand or other finely divided material, the top of which is adjacent or above the level of inlet of the fuel line D³. G² is a removable closing plug upon which is mounted the supporting roller G³.

It will be realized that whereas I have illustrated a practical and operative device and process, nevertheless many changes might be made in the size, shape, number and disposition of parts and in the steps of my process, without departing from the spirit of my invention. I therefore wish my description and drawings to be taken as in a broad sense diagrammatic and illustrative.

The use and operation of my invention are as follows:

In association with the fire pot of an oil burner of any suitable type, I provide an oil pilot light. Preferably I aperture the bottom of the fire pot and align with the aperture, beneath the firepot, a fuel mixing and

combustion chamber. In the form illustrated herewith I show a combustion chamber surrounded by an annular air chamber, the separating wall being provided with a plurality of apertures. In the bottom of the combustion chamber I provide a layer of sand or any other material operative for the same function, and introduce the liquid fuel, preferably at approximately the level of the bed of sand. The air necessary to support combustion is pumped by the fan F^6 through the line F^5 , the chamber F^3 and the passages F^4 , to the combustion chamber. The liquid fuel is dispersed in the sand and coats the various particles with a thin liquid layer. This action damps out any lag or irregularity of flow due to the pumping of the fuel in small bodies or drops.

The fuel may be initially ignited, for example by a gas torch. When combustion is in progress, the vaporized fuel which fills the combustion chamber receives the air necessary for combustion through the apertures F^2 . The streams of air so admitted mix with the vapor to form a combustible mixture, the combustion having the appearance of a plurality of tubular jets of flame converging in the center of the chamber, mingling and rising as a single flame through the apertures F^{14} , F^{12} .

The fuel flow and air pressure are so regulated that the flame pressure at the upper neck of the pilot light chamber is greater than the static pressure of the fire pot when the fan or blower B^1 is in operation, thus preventing back pressure in the pilot light chamber.

During combustion carbon will coat the walls of the chamber. The blasts of air from the apertures maintain open passages in the carbon lining so formed, the passages increasing in cross section toward the center of the chamber. This lining builds out until the carbon reaches a point where the flame burns it off. When a balance is reached between the tendency of the carbon to deposit, and the tendency to burn off, I have a lining of incandescent carbon. When this balance is reached, the temperature of the chamber is approximately 1800° F. and will not rise higher. At this temperature some of the carbon dioxide breaks down to $CO+O_2$, and the result is a flame rich in carbon monoxide and in oxygen. This flame can play indefinitely against the lining of the firepot

without depositing carbon on its exposed surfaces.

I claim:

1. The combination with an oil burner having a firepot and means for supplying air thereto under pressure, of an oil burning pilot light associated with said firepot, said pilot light including a mixing chamber, means for supplying a liquid hydrocarbon thereto, means for supplying air under pressure to said mixing chamber, the mixing chamber being positioned beneath the bottom of the main firepot, the firepot being apertured in line with the central opening of the pilot light mixing chamber, the diameter of said aperture being substantially less than the maximum diameter of said mixing chamber.

2. The combination with an oil burner having a firepot and means for supplying air thereto under pressure, of an oil burning pilot light associated with said firepot, said pilot light including a mixing chamber, means for supplying a liquid hydrocarbon thereto, means for supplying air under pressure to said mixing chamber, the mixing chamber being positioned beneath the bottom of the main firepot, the firepot being apertured in line with the central opening of the pilot light mixing chamber, the diameter of said aperture being substantially less than the maximum diameter of said mixing chamber, there being independent air supply members extending to the firepot and to the mixing chamber of the pilot light, and an independent fuel line extending to the lower portion of the mixing chamber of the pilot light.

3. The combination with an oil burner having a firepot and means for supplying air thereto under pressure, of an oil burning pilot light associated with said firepot, said pilot light including a mixing chamber, means for supplying a liquid hydrocarbon thereto, means for supplying air under pressure to said mixing chamber, the mixing chamber being positioned beneath the bottom of the main firepot, a communicating aperture being provided, the diameter of said aperture being substantially less than the maximum diameter of said mixing chamber.

Signed at Chicago, county of Cook and State of Illinois, this 29th day of July, 1925.
JAMES L. BREESE, Jr.
